UNITED STATES PATENT OFFICE.

HAAKON A. MARTIN, OF DAYTON, OHIO, ASSIGNOR TO THE NATIONAL CASH REGISTER COMPANY, OF DAYTON, OHIO, A CORPORATION OF OHIO, (INCORPORATED IN 1906)

FILING-CABINET.

1,329,539.

Specification of Letters Patent.

Patented Feb. 3, 1920.

Application filed June 5, 1914. Serial No. 843,161.

To all whom it may concern:

Be it known that I, HAAKON A. MARTIN, a citizen of the United States, residing at Dayton, in the county of Montgomery and 5 State of Ohio, have invented certain new and useful Improvements in Filing-Cabinets, of which I declare the following to be a full, clear, and exact description.

This invention relates to filing or storage 10 cabinets and has more particular relation to that class of filing cabinets used as a storage place for devices or articles adapted to be removed for temporary use outside of the cabinet and subsequently replaced.

15 One of the principal objects of the invention is to provide means for the convenient storage and handling of the articles filed in the cabinet.

Another object is to provide means where- 20 by an article once having been removed from the cabinet cannot be replaced completely except by some authorized person or persons, thereby indicating clearly which of said articles have been removed.

25 The present invention and the substantial parts thereof are capable of various uses other than in the disclosed embodiment wherein the invention is applied particu- 30 larly to a cabinet for filing destination of control devices, such as are described in two co-pending applications for Letters Patent of the United States, filed by Haakon A. Martin, one of these patent applications having been filed February 6, 1915, Serial 35 No. 6490, and the other June 20, 1914, Serial No. 846,222.

Reference is made here to these applications as the present invention has a direct relation thereto. In the above patent application, No. 6490 is shown and described 40 a railroad ticket issuing machine having mechanism for coöperating with detachable destination or control devices to print and issue tickets. These detachable devices also 45 control totalizing mechanism for accumulating the value of the tickets issued by the machine as a whole and each device is provided with a consecutive printing counter for printing on the tickets the number of 50 the tickets issued to the particular station to which the device is assigned. In the pat-

ent application, Serial No. 846,222, an auditing machine is shown and described, the machine being used to print from the consecutive printing counters of the destination devices upon a detail strip for auditing purposes as the devices pass through the machine. It is desirable to make a record in the auditing machine only from those destination devices which have been used 55 since the last audit was made by the auditing machine, as it would be useless and a waste of time to print from the devices not used during that period.

One of the principal objects of the present embodiment of the invention, therefore, is to construct a filing cabinet for the destination devices so that the auditor, having control of the auditing machine, may detect readily which of the devices have been 60 withdrawn from the cabinet for use in the ticket issuing machine. To this end means are provided in the cabinet for preventing the used destination devices from being completely reinserted into the cabinet so 65 that these devices will project beyond the devices which have not been used. The disabling of these means is under the control 70 of the auditor, so that all of the devices may be fully inserted after a complete audit 75 is made by the auditing machine from the destination devices used in the ticket issuing machine.

With these and incidental objects in view, the invention consists in certain novel features of construction and combinations of parts, the essential elements of which are set forth in appended claims, and a preferred form of embodiment of which is hereinafter described with reference to the 85 drawings which accompany and form part of the specification.

Figure 1 is a front elevation of the cabinet constructed, according to the present invention, omitting some of the slides for carrying their respective destination devices and the plates, preventing the complete insertion of the destination devices after being withdrawn.

Fig. 2 is a right hand side elevation of 100 the cabinet, part of the casing and parts of the interior of the cabinet being broken

away to expose the arrangement and construction of the cabinet more clearly to view.

Fig. 3 is a detail top plan view of a frame and one of the devices pivoted thereon for preventing the complete insertion of a destination device after it has been used.

Fig. 4 shows a top plan view and a view in side elevation of one of the slides for carrying a destination device.

Referring to Figs. 1 and 2 of the above drawings, side plates 1 of the outside casing of the cabinet are fastened on vertical bars 3 and 4 which are rigidly connected at 15 their upper and lower ends to flanges 6 integral with the bottom 7 and top 8 of the casing. The back 9 of the casing is fastened in a similar manner to the rear bars 3 which are bent to form a right angle. 20 Vertical supporting frames or plates 10 are fastened to the top 8 and base 7 of the machine. The plates 10 are cut as shown at 11 (Fig. 2) and the cut portions 12 are bent to form laterally extending flanges 25 upon which plates or slides 13 are supported. The slides are cut at 14 (Fig. 4) and the cut portions are bent to form a right angled projection 15, so that the sides of the bottom of the slides 13 will rest on the 30 flanges 12 and the horizontal portions of projections 15 will extend under the flanges 12 to guide the slides. The flanges 12 have shoulders 16 (Fig. 4) which are engaged by the vertical portions of the projections 35 15 on the slides 13 when the latter are pulled forward to limit the movement of the slides and prevent their withdrawal from the cabinet. The slides 13 are provided to carry the destination devices 17, which are placed 40 on the slides so that their rear ends engage vertical lugs or bent portions 18 on the slides. The slides are moved forward and backward on their supporting flanges 12 by the finger pieces 19. Rearward movement of the slides 13 is limited by the engagement of vertical flanges 20 on the rear 45 ends of the slides with the forward edges of the sides 21 of a frame 22 which, as shown in Fig. 3, is formed in one piece and fastened to the back 9 of the cabinet. There 50 is one of these frames 22 in the rear of each vertical row of slides 13.

The forward edges of the sides of each frame 22 are provided with slots 23 (Figs. 1 and 2) into which projections 24 (Figs. 2 and 3) on pivoted plates 25 extend, the projections 24 serving as pivots for the plates 25. The forward ends of the plates 25, there being one plate for each destination device, 60 rest upon the destination devices when the latter are in normal position, *i. e.*, fully inserted. The uppermost destination device shown in Fig. 2 is in this position. When a destination device is drawn forward by its 65 slide 13 to withdraw it from the cabinet the

device 17 passes out from beneath its plate 25 and the latter is rocked downward by the force of gravity until it rests on a cross rod 26, so that the forward end of the plate is held in the path of the destination device, 70 when the latter is reinserted to limit the movement of the device, but permits the slide 13 to be moved into normal position and against the frame 22. In Fig. 2 the second destination device and slide 13 from 75 the top are shown in these positions. It can readily be seen that the used destination devices project out of the cabinet when reinserted thereby enabling the detection of 80 the devices used.

The cross rods 26, there being one cross rod for each horizontal row of plates 25, are supported at their ends in vertical bars 27 (Figs. 2 and 3). The outer ends of a cross rod 28 supported at the lower ends of the 85 bars 27, pass through forwardly extending arms 29 of bell crank levers 30 fast on a shaft 31. The bars 27 at their upper ends support a cross rod 32, the ends of which are journaled in the forwardly extending 90 arms 33 of bell crank levers 34 fast on a shaft 35. The downwardly extending arms 36 of the bell crank levers 34 normally engage the back 9 of the casing to prevent the disabling frame, comprising the bars 27 and 95 rods 26, from swinging down past normal position shown in Fig. 2. Fast on the right hand end of the shaft 31 is a hand lever 37 which, when moved clockwise, serves to rock the shaft 31 and the bell crank levers 30, 100 thereby raising the disabling frame so that the cross rods 26 elevate the forward ends of the plates 25 which have been rocked out of the paths of the destination devices, thereby to permit the auditor to push the used destination devices back to normal position into engagement with the lugs 18 on their slides 105 13, while the lever 37 is held in disabling position. Arms 38 of the bell crank levers 30 engage the back 9 of the casing to limit 110 the rearward movement of the levers 37. A spring 39, which is connected at one end to the second rod 26 from the bottom and at its opposite end to a lug 40 on the base of the casing, moves the disabling frame and the 115 hand lever 37 back to normal position, when the auditor removes his hand from the hand lever.

For the purpose of preventing an unauthorized person operating the hand lever 120 37 a lock 41 fastened on the right hand side 1 of the casing is provided (Fig. 1). The right hand side bar 27 of the disabling frame carries a stud 42 having a flat surface 43 over which the bolt 44 of the lock passes when 125 moved by the key 45 into locking position to prevent movement of the disabling frame and therefore of the hand lever.

While the form of mechanism herein shown and described is admirably adapted 130

to fulfil the objects primarily stated, it is to be understood that it is not intended to confine the invention to the one form of embodiment herein shown and described, as it is susceptible of embodiment in various forms, all coming within the scope of the claims which follow.

What is claimed is:—

1. The combination with articles or devices to be filed, of a cabinet comprising compartments in which the devices or articles are filed, means normally held in ineffective position but moved to effective position when the articles or devices are moved in one direction in the compartments whereby the articles or devices withdrawn and reinserted may be detected, and devices for returning said means to normal position.
2. The combination with articles or devices to be filed, of a cabinet comprising compartments in which the devices or articles are filed, means normally held in ineffective position but moved to effective position when the devices or articles are moved in one direction in the compartments whereby the articles or devices withdrawn and reinserted may be detected, and mechanism movable independently of the articles or devices for returning said means to normal position.
3. In a cabinet of the class described, the combination of articles filed in the cabinet, a device released as each article is withdrawn for preventing a complete return of the article when reinserted in the cabinet, and mechanism operable to return said devices to unreleased position to permit complete return of the articles.
4. In a cabinet of the class described, the combination of devices filed in the cabinet, means released as each device is withdrawn for preventing a complete return of the devices when reinserted in the cabinet, mechanism operable to return all the released means simultaneously to unreleased position whereby to permit a complete return of all of the devices, and a lock operable to prevent operation of said mechanism.
5. In a cabinet of the class described, the combination with devices or articles to be filed in compartments in the cabinet, of a plurality of elements, one for each compartment, for preventing the complete refiling of a device or article in a compartment after it has been withdrawn therefrom, operative means for simultaneously rendering said ele-

ments effective to permit a complete return of the devices or articles, and means for preventing operation of said common means.

6. In a cabinet of the class described, the combination with devices or articles to be filed in the cabinet, of a plurality of elements, one for each compartment, for preventing complete refiling of a device or article in the cabinet, a hand lever and connections for operating said elements to permit complete refiling of all withdrawn devices or articles, and a lock inaccessible to the operator for said hand lever.

7. In a cabinet of the class described, the combination with devices to be filed therein, of slides one for each device, for carrying the devices into position to be withdrawn from the machine, pivoted elements, one for each device, normally resting on said devices when completely filed and adapted to move into the path of the devices when the devices are withdrawn to prevent complete refiling of the devices, and an operating mechanism for simultaneously moving all of the operated elements out of preventing position.

8. In a cabinet of the class described, the combination with devices to be filed in compartments in the cabinet, of pivoted elements, one for each compartment, normally resting on the devices completely filed and adapted to drop into position to prevent complete refiling of the devices, a frame comprising cross rods passing under said elements, and a hand lever for elevating said frame so that the cross rods will raise the operated elements out of preventing position.

9. In a cabinet of the class described, the combination of devices or articles to be filed in the cabinet, normally inoperative detents moved to operative position when a device or article is withdrawn for preventing complete return of the device or article, and means movable independently of the devices or articles for returning the detents to inoperative position whereby to permit complete return of the devices or articles to the file.

In testimony whereof I affix my signature in the presence of two witnesses.
